UNITED STATES PATENT OFFICE.

EDWIN BURNHAM, OF GLENVIEW, ILLINOIS.

PROTECTIVE COVERING FOR BATHTUBS.

Application filed January 31, 1929. Serial No. 336,577.

This invention relates to improvements in protective covering for bath tubs and the like, and one of the objects of the invention is to provide a protective or temporary cover which is adapted to be placed over a bath tub during the time that the building or room is under construction.

In order to install what is commonly known as built-in bath tubs, it is necessary to put the same into position before the room is finished so that the tile as well as the wall may be properly placed.

The result is that the highly polished or finished porcelain surface of the tub is constantly exposed to injury by sand, paint, plaster and the like, and with the further objection that workmen often place objects into the tub as well as stand in the tub themselves, or use the tub as a support, with the result that the highly polished surface will be injured.

It is one of the objects of the present invention to overcome these difficulties and objections and to provide an improved protecting cover for this purpose and which cover will not only be adjustable to compensate varying sizes of tubs but will be preferably of sufficient strength to support the mechanic, if he desires to stand on the same to work above the tub.

A further object is to provide an improved cover of this character embodying means for protecting the exposed vertical outer faces of the tube to prevent injury to the same by an object striking such surface.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention and in which

Figure 1 is a perspective view of a built-in tub having a protective covering constructed in accordance with the principles of this invention applied thereto.

Figure 2 is a perspective view of one of the cover sections.

Figure 3 is a detail sectional view on lines 3—3, Figures 1 and 6, on an enlarged scale.

Figure 4 is a sectional view taken on line 4—4, Figure 1.

Figure 5 is a sectional view taken on line 5—5, Figure 1.

Figure 6 is a detail view, partly in elevation, partly in section and partly broken away, showing the overlapping or telescoping joint formed between the side panels or shields. 60

Figure 7 is a detail top plan view showing one of the pads or bumpers.

As shown in the accompanying drawings the cover is of sectional construction and may be formed of any desired number of sections. 65 In the present exemplification of the invention, however, three sections are shown. The middle section is preferably formed of spaced parallel side members 10 having laterally projecting flanges 11 at the bottom thereof and laterally deflected flanges 12 at the top thereof extending in a direction opposite to the direction of the flanges 11. 70

Arranged between the side members 10 is a body member 13 preferably of sheet metal 75 which rests upon the respective flanges 11 and is secured thereto in any suitable manner such as by means of fastenings 14.

If desired a reinforce or bracing member 15 may be disposed between the side members 80 10 and may be held in position by being secured to the member 13 by fastening devices as at 16.

The member thus formed may be of any desired size, and protecting elements 17 such as 85 rubber, felt, or the like, may be arranged beneath the flanges 12 and adjacent the outer face of the respective member 10 so that when the section is placed in position upon the top of a bath tub 18 the protecting material 17 90 95 will engage the highly polished upper edge of the walls of the tub to protect the latter from injury when the section is in position and also in the event that the section may be slid along upon the walls of the tub.

Co-operating with the center section are end sections which are formed preferably by means of cross bars 19—20, arranged transverse to the side members 10 and preferably parallel with the reinforcing member 15 and with each other. The members 19 are preferably of angle iron construction while the members 20 are preferably flat, and secured to these members 19 and 20 is a body member 21 constructed of any suitable material such as sheet material. The body portions of the end sections 21 are of a width that when placed in position they will also rest upon the top of the tub. 100

The cross bar 19 of each end section is so arranged and is of such a width that it will project between the side members 10 of the 110

center section and terminate in close proximity to the body portion 13 of the center section and also the side members 10, on the respective sides of the reinforcing member 15.

5 To the respective members 21 are secured protecting elements 22 such as fabric, rubber, or the like some of which may be secured to members 22^a pivotally connected with the member 21 as at 22^b so as to permit the elements 22 to be moved out of the way so as not to interfere with telescoping the cover sections together, and which elements 22 are adapted to rest upon the top edge of the tub.

10 Protecting elements 23 such as rubber or the like may be secured to the lower face of the respective sections 21 and engage and rest upon the top edge of the inner side walls of the tub so that the sections 21 may be slid upon the top of the tub without danger of 15 injuring the tub. At the same time they will 20 form cushions between the end sections and the wall of the tub.

15 It will thus be seen that with this construction the end sections 21 may be adjusted with respect to each other and with respect to the center section so as to compensate varying sizes of tubs.

20 The end sections 21 may be provided with bearings 24 adjacent the front of the tub and also bearings 24^a at the ends thereof, which 25 may be formed as an integral part of the respective sections 21 or may be formed by means of independent members 25 secured to the top of the respective sections to extend 30 therebeyond.

25 The center section may also be provided with a member 26 secured thereto to project beyond the side thereof and is curved or shaped to form a bearing 27 which is in alignment with the bearings 24 on the sides of the 35 respective end sections.

30 In order to protect the outer face of the upright wall of the tub, curtains or shields 28 may be provided. The top edge of the 35 shields or curtains 28 are respectively rolled or curved as at 29 so as to telescope with each other and at the same time the telescoping portion 29 will enter the bearing 27 so that the proximate ends of the curtains or shields 50 will be supported.

35 The respective curtains or shields are supported by the bearings 24 on the respective members 21, while the bearing 27 on the intermediate member supports the telescoping portion of the curtains or shields.

40 An end curtain or shield of similar construction may be pivotally supported by the bearings 24^a and the bearings 24^a are provided on each of the end sections so that a curtain may be employed when either of the end sections 21 is outermost.

45 If desired, bumpers 30 may be provided on the inner faces of the curtains or shields to contact with the outer face of the tub.

50 Thus it will be seen that the curtains or

shields 28 may be adjusted so as to telescope with each other when the ends sections 21 are moved towards each other or when the end sections 21 are adjusted with respect to the center section of the cover to fit smaller tubs. 70 When the end sections 21 are separated, when the cover is in position on the tub, the shields or curtains 28 will also be separated.

75 With this improved construction it will be manifest that the device may be telescoped together or may be knocked down for the purpose of transportation or storage, and the parts may be constructed of such strength so that the cover will serve as a support for a mechanic, if he desires to stand thereupon. 80

85 While in the present exemplification of this invention, the cover sections are shown and described as being built-up elements, it is to be understood that the sections may be formed of stamping.

90 While the preferred form of the invention has been herein shown and described, it is to be understood that various changes may be made in the details of construction and in the combination and arrangement of the several parts, within the scope of the claims, without departing from the spirit of this invention.

95 What is claimed as new is:—

1. A cover for bath tubs and the like embodying end sections and an intermediate central section with which the respective end sections telescope, portions of said sections projecting over and engaging and resting upon the top edge of the tub. 100

105 2. A cover for bath tubs and the like embodying end sections and an intermediate central section with which the respective end sections telescope, portions of said sections projecting over and engaging and resting upon the top edge of the tub, and shield members connected with the cover and depending therefrom adjacent the outer face of the tub.

110 3. A cover for bath tubs and the like embodying end sections and an intermediate central section with which the respective end sections telescope, portions of said sections projecting over and engaging and resting upon the top edge of the tub, and shield members connected with the cover and depending therefrom adjacent the outer face of the tub, said shield members telescoping with each other. 115

120 4. A cover for bath tubs and the like embodying end sections and an intermediate central section with which the respective end sections telescope, portions of said sections projecting over and engaging and resting upon the top edge of the tub, and shield members swingingly connected with the cover and depending therefrom adjacent the outer face of the tub. 125

130 5. A cover for bath tubs and the like embodying end sections and an intermediate

- section with which the respective end sections telescope, all of said sections having edges resting on the top of the tub, the end sections having edges extending laterally beyond the outer edge of the intermediate section. 5 to which flange one of said sections is movable 65 in telescoping relation with the other section, and shield members supported by and depending from said sections adjacent the outer face of the tub wall.
6. A cover for bath tubs and the like embodying end sections and an intermediate section with which the respective end sections telescope, all of said sections having edges resting on the top of the tub, the end sections having edges extending laterally beyond the outer edge of the intermediate section, and protecting pads carried by said edges of said section and disposed between said edges and the top of the walls of the tub. 10 70
7. A cover for bath tubs and the like embodying end sections and an intermediate section with which the respective end sections telescope, all of said sections having edges resting on the top of the tub, the end sections having edges extending laterally beyond the outer edge of the intermediate section, and protecting shields supported by and depending from certain of said sections against the outer face of the wall of the tub. 15 75
8. A cover for bath tubs and the like embodying end sections and an intermediate section with which the respective end sections telescope, all of said sections having edges resting on the top of the tub, the end sections having edges extending laterally beyond the outer edge of the intermediate section, and protecting shields swingingly supported by and depending from certain of said sections against the outer face of the wall of the tub. 20 80
9. A cover for bath tubs embodying a section having a depressed body portion extending into the tub, the lateral edges of said section engaging and resting upon the top edge of the tub, a second section movable over the first said section, said second section having edges extending laterally beyond the said edges of the first said section and resting upon the top edge of the wall of the tub, and an upright flange carried by one of said sections to fill the space between the depressed portion of the first said section and the body of the second recited section and with respect to which flange one of said sections is movable in telescoping relation with the other section, the said depressed portion of said section serving to maintain the cover against lateral displacement with respect to the tub. 25 85
10. A cover for bath tubs embodying a section having a depressed body portion extending into the tub, the lateral edges of said section engaging and resting upon the top edge of the tub, a second section movable over the first said section, said second section having edges extending laterally beyond the said edges of the first said section and resting upon the top edge of the wall of the tub, an upright flange carried by one of said sections to fill the space between the depressed portion of the first said section and the body of the second recited section and with respect to which flange one of said sections is movable in telescoping relation with the other section, and protecting pads disposed between the top edge of the tub walls and the engaging edges of the respective sections of the cover. 30 90
11. A cover for bath tubs embodying a section having a depressed body portion extending into the tub, the lateral edges of said section engaging and resting upon the top edge of the tub, a second section movable over the first said section, said second section having edges extending laterally beyond the said edges of the first said section and resting upon the top edge of the wall of the tub, an upright flange carried by one of said sections to fill the space between the depressed portion of the first said section and the body of the second recited section and with respect to which flange one of said sections is movable in telescoping relation with the other section, and shield members supported by and depending from the said sections adjacent the outer face of the tub wall, said shield members telescoping with each other. 35 95
12. A cover for bath tubs embodying a section having a depressed body portion extending into the tub, the lateral edges of said section engaging and resting upon the top edge of the tub, a second section movable over the first said section, said second section having edges extending laterally beyond the said edges of the first said section and resting upon the top edge of the wall of the tub, and an upright flange carried by one of said sections to fill the space between the depressed portion of the first said section and the body of the second recited section and with respect to which flange one of said sections is movable in telescoping relation with the other section, the said depressed portion of said section serving to maintain the cover against lateral displacement with respect to the tub. 40 100
13. A cover for bath tubs embodying a section having a depressed body portion extending into the tub, the lateral edges of said section engaging and resting upon the top edge of the tub, a second section movable over the first said section, said second section having edges extending laterally beyond the said edges of the first said section and resting upon the top edge of the wall of the tub, an upright flange carried by one of said sections to fill the space between the depressed portion of the first said section and the body of the second recited section and with respect to which flange one of said sections is movable in telescoping relation with the other section, and protecting pads disposed between the top edge of the tub walls and the engaging edges of the respective sections of the cover. 45 105
- In testimony whereof I have signed my name to this specification on this 25th day of January, A. D. 1929.

EDWIN BURNHAM.
